UNITED STATES PATENT OFFICE

BENJAMIN C. VANDUZEN, OF CINCINNATI, OHIO.

AUTOMATIC GATE FOR ELEVATORS.

SPECIFICATION forming part of Letters Patent No. 258,827, dated May 30, 1882.

Application filed September 5, 1881. (No model.)

To all whom it may concern:

Be it known that I, BENJAMIN C. VANDUZEN, of the city of Cincinnati, county of Hamilton, and State of Ohio, have invented 5 certain new and useful Improvements in Automatic Gates for Elevators, of which the following is a specification.

The object of my invention is to provide a guard for elevator-hatchways which shall be 10 automatically opened and closed by the elevator in its passage either up or down the hatchway; and the principal feature of my invention consists in a novel mechanism whereby this object is accomplished.

15 Various subordinate features will be obvious from the following description.

In the drawings forming a part of this specification, Figure 1 represents my invention as applied to a gate, one end of which is pivoted 20 at one side of the hatch, the other end being free to rise, the gate in this figure being represented as closed. Fig. 2 represents the same devices shown in Fig. 1, the gate being opened. Fig. 3 is a plan view of Fig. 1. Fig. 4 represents my invention as applied to a gate which 25 slides vertically in appropriate ways. Fig. 5 is a detached view, showing the preferred form of device by the operation of which the elevator is enabled to pass the gate, when so desired, on any floor without raising it.

A is the platform of the elevator, and A' the vertical posts by which the platform is suspended.

B represents the guideways, situated at either 30 side of the elevator-shaft.

To the upright A', at one side of the elevator, is attached the plate a, in a manner to be hereinafter described. The edge of this plate projects slightly beyond the face of the upright A'.

35 A shaft, C, is journaled at one end in a bearing, b, attached to the guideway B near the floor, the other end of the shaft C being journaled in the post C'. To this shaft C, and near the guideway B, is secured a friction-wheel, D, 40 the position of this wheel on the shaft being such that the plane of its revolution will be in a line with the plate a, so that as the elevator passes up and down the edge of the plate a will come in contact with the periphery of the 45 wheel D, the friction between the plate and wheel causing the latter to revolve. The length

of the plate a is just equal to the circumference of the wheel D, so that the latter will be caused to turn only once around as the elevator carrying the plate a passes up or down.

55

To the end of the shaft C which is on the outer side of the post C' is secured the wheel D', from the outer face of which projects the crank-pin d. To the upper end of the post C' is pivoted one end of the gate E, the other end of which rests in a support, C², at the opposite side of the hatchway. A rod, d', is connected at one end to the crank-pin d on the wheel D', the other end of said rod being connected at d² to the upper bar of the gate E. 65 The gate E is preferably provided with the usual counterbalance-weight E'.

Suppose, now, the elevator-platform A to be below the floor upon which it is desired to land, the gate E remains closed until the elevator in 70 ascending brings the end of the plate a in contact with the wheel D, as shown in Fig. 1. The elevator now continuing to ascend, the friction between the plate a and the periphery of the wheel D causes the latter to revolve, 75 and by this means the shaft C and wheel D' are caused to revolve, carrying the crank-pin d to the upper side of the wheel D', and the rod d' is thus raised, which in turn elevates the free end of the gate E until the various 80 parts occupy the position shown in Fig. 2, the platform of the elevator being on a level with the floor. The plate a is so situated that when the platform of the elevator is on a level with the floor the center of the plate will be opposite to the center of the wheel D', as shown in Fig. 2. As soon, now, as the elevator starts 85 either up or down, it matters not which, the wheel D' is caused to revolve, and the crank-pin d is carried around to the lower side of the 90 wheel, and the free end of the gate is thus caused to descend until it rests in the support C², by which time the end of the plate a will have reached a point opposite the center of the wheel D, and a further movement of the 95 elevator will free the plate from contact with the friction-wheel, and the gate will remain at rest until the plate a again comes in contact with the wheel D.

The length of the plate a and the circumference of the wheel D are preferably such that the gate will remain at rest until the platform 100

of the elevator reaches a point about eighteen inches from the floor; but this arrangement, as will readily be seen, may be varied at the will of the builder.

5 The gate E may consist of a single bar, or be constructed upon the principle shown in the drawings, in which a lower rail, e, is employed, which rail is suspended from the upper or main bar by a number of connecting-strips in such a manner that when the gate is elevated it will fold up, as shown in Fig. 2.

When for any reason it is preferable to employ a gate which shall slide up and down, I preferably employ the arrangement shown in Fig. 4.

10 To the top of the gate F is connected one end of a steel or iron ribbon, f, the other end of which, after passing over the pulley f', is wound onto the drum F', which is supported by suitable bearings. To one end of the drum F' is connected the toothed wheel G, which is of considerably less diameter than the drum, and over this wheel passes the drive-chain G', one end being connected to the crank-pin d on the wheel D', the other end of said chain being provided with a weight, g, for the purpose of keeping the chain tight.

15 When the gate F is closed the crank-pin d is at the top of the wheel D', and when the plate a comes in contact with the wheel D' as the elevator ascends or descends the wheel is caused to revolve, carrying the crank-pin to the bottom, which, by means of the drive-chain G' and toothed wheel G, causes the drum F' to revolve, and the ribbon f is wound on the drum, and the gate F is thereby elevated. When the platform of the elevator leaves the floor the wheel D' revolves, carrying the crank-pin d towards the top, and the gate F, by its 20 own weight, gradually descends.

25 Instead of the ribbon f, a cord may be employed, if preferred; but I prefer the ribbon.

30 To permit the elevator to pass a certain floor without interfering with the gate on said floor, various devices may be employed; but the device which I prefer is that shown in the drawings.

35 The plate a is secured to the upright A' by means of the oblique slots h and pins h' in such a manner that when the plate is raised slightly it will also be moved slightly toward the center of the elevator, so that as the elevator passes up and down the edge of the plate will not come in contact with the periphery of the 40 wheel D, and thus the elevator-gate is not interfered with. To elevate this plate a, I employ the knuckle-joint H, the lower member of which is connected to the top of the plate a, and the upper member of which is connected to the side of the upright A'. The up-

per member is provided with the weighted lever I, extending toward the center of the elevator, the tendency of which lever is to keep the two members of the knuckle-joint H in a line with each other, and when these two members are thus in a line with each other, as shown in Figs. 1 and 2, the plate a cannot be raised, and the edge of the plate will therefore come in contact with the wheel D. If now it is desired to pass a gate on any floor, 45 the person on the elevator lifts up on the lever I, and the parts assume the position shown in Fig. 5, the plate a being raised up and moved away from the wheel D. The lever I is held in this position until the plate a has passed 50 the wheel D, when it is released and by its own weight falls down, thus restoring the various parts to their former position.

55 It may be here remarked that it matters not which way the elevator moves, the operation 55 upon the gate will be the same, as will be readily understood from the drawings and the foregoing description.

60 What I claim as new and of my invention, and desire to secure by Letters Patent, is— 65

1. The combination of an elevator provided with the plate a, friction-wheel D, attached to shaft C, crank D' d, connecting-rod d', and the gate E, one end of the connecting-rod d' being connected to the crank and the other to the 70 gate, substantially as described.

2. The combination of the gate E, friction-wheel D, and connecting and operating mechanism, and the plate a, adjustably attached to the elevator, and capable of being adjusted to 75 impinge against the friction-wheel D or pass it without coming in contact therewith as the elevator passes up or down, substantially as and for the purposes described.

3. The combination of the upright post A' 80 of an elevator, the plate a, provided with the oblique slots h, which engage with the pins h', projecting from said upright post, the knuckle-joint H, friction-wheel D, and the gate E, and connecting and operating mechanism, substantially as and for the purposes specified.

4. The combination of the friction-wheel D and plate a, provided with oblique notches h, which engage with pins h', projecting from the upright A', and the knuckle-joint H, the lower 85 member of said joint being attached to the plate a and the upper member to the upright A', said upper member being provided with the weighted lever I, substantially as and for the purposes specified.

BENJAMIN C. VANDUZEN.
